2 Sheets-Sheet 2

<img alt="Technical drawing of a mechanical assembly labeled Fig. 4. The drawing shows a complex arrangement of components including a main frame, various shafts, bearings, and a central vertical column with a gear assembly. Numerous parts are numbered with reference codes such as 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, NARROWING DEVICE FOR FLAT KNITTING MACHINES

Woldemar Heinitz, Chemnitz, Germany, assignor to Schubert & Salzer Maschinenfabrik Aktiengesellschaft, Chemnitz, Germany

Application March 29, 1937, Serial No. 133,732
In Germany April 7, 1936

2 Claims. (Cl. 66—89)

The present invention relates to a narrowing device for flat knitting machines capable of being used for diamond narrowing as well as for fabric narrowing.

5 Several devices for controlling the wedge narrowing as well as the diamond narrowing are known. Whereas in connection with footing machines a control of the wide or broad wedge narrowing devices, lying at the outer side, may 10 be possible and the movement of the small diamond narrowing devices arranged at the inner side is effected by a shifting movement due to the movement of the broad wedge narrowing devices arranged at the outer side, that is to say only 15 toes of stockings may be produced, machines producing stockings in a single operation must be so constructed, that the diamond narrowing devices also may be moved independently for the purpose of fabric narrowing. To obtain this object the narrowing bars for the wedge narrowing device and the diamond narrowing device respectively are connected by means of a slide to the narrowing stop in such a manner, that besides the adjustment mentioned above for the 20 production of the toes, an adjustment for fabric narrowing also is possible which is produced by the diamond narrowing devices only.

25 As the narrowing bars for the diamond narrowing devices do not have their own drive and are held by small racks and blade springs only, the manufacture and adjustment of which offers difficulties, unexact adjustments of the narrowing device are unavoidable.

30 A further drawback is the complicated movement over one needle of the diamond narrowing device for the diamond narrowing at the toe of the stocking by means of several lever ratios.

35 All these drawbacks are obviated by the device according to the present invention. Due to the fact, that the slides present in the machine are 40 provided with a recess for movement over one needle, the diamond narrowing devices may, during the adjustment of the slides, be adjusted at each narrowing operation for the distance of two 45 adjacent needles in the most simple manner and without fault. Whereas the wedge narrowing devices are directly coupled to the slide, the diamond narrowing devices are no longer controlled by the wedge narrowing devices, but are 50 also resiliently pressed against their slide by means of stops fixed to the narrowing bars. Hereby a positive control free of objections is obtained for the wedge narrowing devices as well as for the diamond narrowing devices excluding 55 any sources of faults. The stops are fixed upon

the narrowing bars of the diamond narrowing devices in such a manner, that the diamond narrowing devices in the normal position of the slides rest against the wedge narrowing devices. Therefore, while in the one position of the slides, 5 i. e. the normal position, both narrowing devices lying against each other may be used as a narrowing device for carrying out narrowings, in the other position, i. e. the rack position, the production of the toes of stockings is possible. 10

To allow the production of fabric narrowings by means of the small diamond narrowing devices lying at the inside, the control of the two narrowing devices is distributed over two slides one of which controls the wedge narrowing device only, while the other slide controls the diamond narrowing device only and is formed again as rack slide. The narrowing bars of the diamond narrowing devices are under the action of springs held against the rack slide by means of 20 stops, while the narrowing bars of the wedge narrowing devices may be coupled or uncoupled with the narrowing stop by means of the second slide. The adjustment of the stops upon the narrowing bars of the diamond narrowing devices is effected in such a manner, that the diamond narrowing devices in the coupled position of the slides rest against the wedge narrowing devices. 25

30 It is therefore possible now to operate with both narrowing devices simultaneously as well as with the diamond narrowing device alone. Due to the fact, that the slides, controlling the diamond narrowing devices, are provided with a recess for movement over one needle, the manufacture of the stocking toe explained already 35 may be effected.

35 In the accompanying drawings one embodiment of the invention is shown by way of example, illustrating the two narrowing devices of a single 40 division necessary for the two operating directions of the thread guide bars.

45 In the drawings:

Fig. 1 is a view of the complete narrowing device, showing the slides in the normal position for the use of the individual narrowing devices pushed together for effecting fabric narrowings.

45 Fig. 2 is a side view of Fig. 1.

50 Fig. 3 is a broken away view similar to Fig. 1, showing the position of the narrowing devices for effecting wedge narrowings, and

55 Fig. 4 illustrates a view similar to Fig. 1 with disengaged wedge narrowing devices for using the diamond narrowing devices alone for the purpose of effecting narrowings.

Mounted upon a narrowing spindle 3, provided with a right-hand thread 1 and left-hand thread 2, and a shaft 4 are narrowing stops 5, 6 which are guided in a well known manner and may by means of the spindle be periodically laterally adjusted corresponding to alterations in the working width. Vertically adjustable mounted in the narrowing stop 5 is a slide 7 and a rack slide 8. Also vertically adjustable mounted in the narrowing stop 6 is a slide 9 and a rack slide 10. The slide 7 serves for controlling the bar 12, carrying the wedge narrowing device 11, whereas the slide 9 serves as control for the bar 14, carrying the wedge narrowing device 13. The control of the bar 12 is effected by stops 15, 16 mounted upon said bar between which the slide 7 may be inserted. The control of the bar 14 is effected in the same manner by means of stops 17, 18 mounted upon said bar between which the slide 9 may be inserted. The slide 7 is provided with two notches 19, 20 in which a blade spring 21 fixed to the stop 5 may engage to hold the slide in its adjusted position. The adjustment of the slide is effected by a handle 22 fixed to said slide. In the same manner the slide 9 is provided with two notches 23, 24 in which a blade spring 25, fixed to the stop 6, may engage. A handle 26 fixed to the slide 9 serves for the purpose of adjusting said slide. The lower end 27 of the rack slide 8 is provided at one side with a recess. Fixed upon the narrowing bar 29, carrying the diamond narrowing device 28, is a stop 30 pressed against the rack slide 8 by means of a spring 31 one end of which is connected to the narrowing bar 29, whereas the other end is connected to the narrowing stop 5. The rack slide 10 also is provided with a lateral recess at its lower end 32. Fixed upon the narrowing bar 34, carrying the diamond narrowing device 33, is a stop 35 which in a manner similar to that described above is pressed against the rack slide 10 by means of a spring 36 connected with its ends to the narrowing bar 34 and the narrowing stop 6 respectively. Pins 37 and 38 are fixed to the rack slide 8 vertically above each other and these pins extend through a slot 39 provided in the narrowing stop 5. In the same manner pins 40, 41 are fixed vertically above each other to the rack slide 10 which pins extend through a slot 42 provided in the narrowing stop 6.

Arranged between the pins 37, 38 and 40, 41 respectively is a rod 43 which is fixed to lever arms 44 pivotally mounted upon the narrowing spindle 3. A pull rod 45 having a recess at its upper end 46 may be engaged with said rod 43 by means of a cam or the like, not shown in the drawings, by which said rod 45 is swung or oscillated in such a manner, that the recess at its upper end 46 engages the rod 43.

Fig. 1 illustrates the narrowing device in the position for effecting fabric narrowings.

If the levers 44 are in the position shown in Fig. 2, the rod 43, actuating the rack slides 8 and 10, occupies a position in which the lower recessed ends 27 and 32 respectively may come into the path of the stops 30 and 35 fixed upon the bars 29 and 34 carrying the diamond narrowing devices 28 and 33 respectively. The diamond narrowing devices 28 and 33 are, by means of the springs 31 and 36, pressed against the wedge narrowing devices 11 and 13 respectively and each of them forms a uniform narrowing device.

The slides 7 and 9 are by means of the handles 22 and 26 depressed and by the leaf springs 21

and 25 engaging the upper notches 19 and 23 respectively said slides 7 and 9 are held in their adjusted position. The lower ends of the slides 7 and 9 lie between the stops 15, 16 and 17, 18 respectively of the bars 12 and 14, so that in a well known manner the narrowing stops 5 and 6 arranged upon the threads 1 and 2 of the spindle 3 may actuate the wedge narrowing devices 11 and 13 respectively.

If small narrowing devices only are required, the slides 7 and 9 are lifted by means of the handles 22 and 26 respectively, so that the blade springs 21 and 25 may engage the lower notches 20 and 24 respectively, so as to hold the slides 7 and 9 in this adjusted position. The bars 12 and 14 are in this manner disengaged from the slides 7 and 9 respectively. The wedge narrowing devices 11 and 13 may be shifted laterally, so that the diamond narrowing devices only occupy the operative position as shown in Fig. 4.

In case the narrowing device is used for the manufacture of a stocking toe, the individual elements occupy the position shown in Fig. 1.

Shortly before picking up the loops, the pull rod 45 is moved in the direction of the arrow X, so that its upper recessed end 46 engages the rod 43, whereupon the rod is drawn downwardly in the direction of the arrow y (Fig. 2).

The rod 43 in its downward movement takes with it the two rack slides 8 and 10, so that their recessed ends 27 and 32 come out of the path of the stops 30 and 35 respectively, and by means of the slides 8 and 10 the narrowing bars 29 and 34 together with the diamond narrowing devices 28 and 33 fixed upon them are separated from the wedge narrowing devices 11 and 13 respectively for the amount of the rack width which corresponds to one needle pitch, whereby the take-up position shown in Fig. 3 is obtained. With the individual elements in this position taking up is effected, whereupon the pull rod 45 is lifted again and disengaged. The diamond narrowing devices 28 and 33 are, by the tension of the springs 31 and 36 respectively brought into contact again with the wedge narrowing devices 11 and 13 respectively. The rack and the tickling off is now effected in well known manner with the narrowing devices lying against each other.

By means of this positive control of the wedge narrowing devices 11 and 13 and the diamond narrowing devices 28 and 33, the narrowing devices are moved in the manner required for the manufacture of the toe portion of a stocking in a manner free of objections and excluding any faults.

What I claim is:

1. A narrowing device for flat knitting machines, comprising a narrowing spindle carrying a right-hand thread and a left-hand thread, a narrowing stop arranged upon each of said threads, two narrowing bars each carrying a wedge narrowing device, two other narrowing bars each carrying a diamond narrowing device, a slide in each of said narrowing stops adapted to cooperate one with one of said two narrowing bars carrying a wedge narrowing device and the other with the other of said two narrowing bars carrying a wedge narrowing device, and a second slide in each of said narrowing stops adapted to be operatively connected the one with the one and the other with the other of said two other narrowing bars carrying said diamond narrowing devices, the arrangement being such, that the two sets of slides may selectively as well as

simultaneously be brought into operative position.

2. A narrowing device for flat knitting machines, comprising a narrowing spindle having a right-hand thread and a left-hand thread, 5
5 a narrowing stop arranged upon each of said threads, wedge narrowing bars slidably arranged in the machine, abutment stops mounted upon each of said wedge narrowing bars, a slide in each of said narrowing stops cooperating with said 10
10 abutment stops to control said wedge narrowing bars, a leaf spring fixed to each of said narrowing stops adapted to engage notches provided in the free end of each of said slides, a handle attached to each of said slides for manually 15
15 shifting said slides, diamond narrowing bars

slidably arranged in the machine, springs connecting said narrowing stops to said diamond narrowing bars, an abutment stop fixed on each of said diamond narrowing bars, a slide in each of said narrowing stops recessed at its lower 5 end and adapted to engage said abutment stop provided on the corresponding diamond narrowing bar, pins fixed to said slides one above each other and extending through slots in said narrowing stops, a cross rod swingably connected to 10 said narrowing spindle, a swingable rod adapted to engage said cross rod and to be moved up and down for shifting said slides cooperating with said diamond narrowing bars.

WOLDEMAR HEINITZ. 15
